UNITED STATES PATENT OFFICE.

JAMES FRANKLIN COLLINS, OF PROVIDENCE, RHODE ISLAND.

METHOD OF TREATING DECAYED SPOTS AND CAVITIES IN LIVING TREES.

1,270,010.

Specification of Letters Patent. Patented June 18, 1918.

Application filed March 24, 1917. Serial No. 157,257.

(DEDICATED TO THE PUBLIC.)

To all whom it may concern:

Be it known that I, JAMES FRANKLIN COLLINS, a citizen of the United States of America, and an employee of the Department of Agriculture of the said United States, residing at Providence, in the county of Providence, State of Rhode Island, (whose post-office address is Providence, Rhode Island,) have invented a new and useful Method of Treating Decayed Spots and Cavities in Living Trees.

This application is made under the act of March 3, 1883, chapter 143 (22 Stat., 625), and the invention herein described and claimed may be used by the Government of the United States, or any of its officers or employees, in the prosecution of work for the Government, or any person in the United States, without payment to me of any royalty thereon.

The object, characteristic features and scope of my invention will be more readily understood from the following description taken in connection with the accompanying drawings, wherein:

Figure 1 is an external or surface view of a cavity filled according to my method, excepting that the outer surface of the filling has not yet been waterproofed.

Fig. 2 is a cross-section of the trunk shown in Fig. 1, made at the point indicated by the broken line, X—X.

Fig. 3 is a cross-section of another trunk through the middle of a cavity, showing another convenient method of placing the strips of wood.

Fig. 4 is a cross-section of a trunk through the middle of a cavity which has been partially filled with strips of wood.

Fig. 5 is a cross-section of a trunk through the middle of a cavity, showing another convenient method of placing the strips of wood in a partially filled cavity.

Fig. 6 is a cross-section of a trunk through the middle of a cavity, showing a method of bolting heavy strips, or several strips, of wood to the sides of a cavity by means of metal bolts.

For the sake of clearness in showing the strips of wood the nails, screws, staples, or bolts used for fastening the strips of wood in the cavity have not been indicated in Figs. 1 to 5, inclusive.

In all the figures W represents the wood, and B the bark of the living tree. 55

My method consists in filling the cavity with strips of wood of any convenient thickness, length or shape; to fit the irregularities of the cavity either with or without bending the strips. The strips first put in place are nailed, stapled, screwed, bolted or otherwise fastened to the waterproofed walls of the cavity and each succeeding strip or layer of strips is waterproofed and nailed or otherwise fastened to those already in 65

place. The joints between strips are shown at A and G in Figs. 1 and 2. The numbers 1 to 15 on the wood strips in Figs. 2 and 3 represent the order in which these strips are nailed or fastened in place. These strips 70 of wood may be impregnated with creosote or some other wood preservative before being fastened in place. Before being waterproofed the strips of wood may be trimmed to fit the particular part of the cavity in 75

which each is to be placed. The interstices between strips may be filled, as the work progresses, with any suitable plastic or adhesive substance, such as asphalt, tar, pitch, paint, elastic cement, or shellac. Large 80

spaces or interstices between or beneath strips may be filled with a thick or pasty mass of suitable plastic or adhesive substance such as asphalt, tar, pitch, paint or some other similar preparation mixed with 85 sawdust, wood pulp, excelsior, shavings, or even sand, burlap, rags, straw, or bran. Several such places are indicated by the thicker places in the lines in Figs. 2 to 6, inclusive. 90

In long cavities the nails, staples, screws, or bolts in the strips, and the strips themselves, may be so placed in the cavity that at least one close or tight joint (across which there are no nails, staples, screws, or bolts) 95 extends lengthwise nearly or quite the whole length of the cavity and from the outer surface of the filling nearly or quite to the back of the original cavity. This joint or joints may be straight in cross-section or 100 more or less zigzag, as shown at A in Fig. 1 and at A—C in Fig. 2 and by the heavy zigzag line in Fig. 3. The advantage and primary object of a joint of this sort is to provide a line or articulation that can 105 readily open as the woody parts of the

trunk regularly shrink or contract during periods of freezing weather, and thus prevent the filling itself from breaking away or separating from the wall of the cavity 5 under the conditions mentioned, or under conditions similar thereto. In narrow cavities only one such joint is recommended, but in wider and shallower cavities two or even more such joints may be better than one. 10 Under such conditions it may be advisable to bolt the ends of long fillings as indicated below.

The strips of wood may extend the entire length of the cavity or in undercut cavities 15 may be divided into sections, depending upon which form of strip may be best adapted for the condition of the particular cavity. They may be placed in the cavity in any order or position in which they can be 20 placed or handled to the best advantage, of course varying more or less with differently shaped cavities. Each succeeding strip should be so placed as to bind or lock those below it in place. They may be trimmed to 25 fit roughly the portion of the cavity in which they are to be placed, or they may be relatively thin strips which can be bent and readily nailed in position; the former usually will be best in short cavities and the latter best in long or undercut cavities. 30 Generally some such arrangement of the strips as that shown in section in Figs. 2 and 3 will be found most advantageous in the ordinary cavity, as some such general arrangement as this usually permits greater freedom in driving the nails or staples or in placing the screws or bolts in position through the strips. The exposed edges of 35 the strips at the surface of the filling may be smoothed off at the line of the cambium, as shown in Fig. 2; or they may be trimmed back to a line behind the cambium and one, two, or more, thin strips of wood of the proper thickness to bring it to the cambium 40 line nailed, stapled, or bolted over them to form a surface layer, as shown in Fig. 3. Finally the exposed surface of the filling may be thoroughly waterproofed with tar, paint, asphalt, or some other suitable substance. 45 In long shallow cavities where there is considerable sway to a trunk or branch it may be necessary to place a bolt through the filling near each end, and perhaps elsewhere, in order to prevent the ends working loose 50 before they become covered by the new growth of wood and bark. Under such conditions an ordinary bolt passing through the filling and trunk, e. a coach bolt passing through the filling and into the trunk, may 55 be used. Either type of bolt should pass through a wide metal washer, or broader plate of metal which extends partially or entirely across the outer face of the filling. The bolts should not pass across one of the 60 unnailed joints, such as A—C in Fig. 2; and

in filling the cavity a superimposed space of an inch or more should be left free of nails in each strip at the point where each bolt is to be located. At these points a bit may be used to bore the holes for the bolts through the completed filling without encountering any nails. The best position for such a bolt is indicated by the broken line Z—Z, in Fig. 3.

A modification of the method described above, and one which at times serves all practical purposes even better than the one already described, although it may not look as neat and finished, consists essentially in partially filling the cavity with strips or 70 blocks of wood in some such manner as described above. Three methods of placing these strips are indicated in section in Figs. 4, 5, and 6. In all cases the outer edges of the strips should be trimmed at the cambium line so that they extend from the cambium at least an inch out across the original cavity, continuing the general contour of the woody part of the trunk, as shown at D in Figs. 4, 5, and 6. When the new growth of 80 wood and bark has grown over the outer edges of these strips, new strips can be put in place, as indicated by the dotted lines E in Figs. 4, 5, and 6. Fig. 6 represents a 85 method of bolting two or more strips to the sides of a cavity by means of double-headed or chamfered iron or steel bolts (F). The bark is cut away just enough to allow the washer under the nut at the outer end of the bolt to be screwed up firmly against the 90 wood, in order to draw the strips within the cavity firmly against its sides by means of the chamfered end of the bolt. At times it may be advisable to reverse the ends of the bolt and have the nut inside the cavity. 95

The above described methods of filling cavities overcome at least two of the most serious defects in cement filled cavities, and at least the main defect in most of the asphalt filled cavities. The advantages of the 100 herein described method over cement are (1) the slight flexibility of the filling under strain of swaying trunk and branches, a flexibility very similar to that of the tree itself; (2) the greatly reduced possibility 105 of the filling pulling or breaking away from the wall of the cavity and thus allowing water, decay-producing germs, insects, or debris to enter between filling and wall of cavity. The main advantages of the herein described method over many cavities filled with asphalt mixtures, or similar plastic substances, is the practical impossibility for the filling to drop away by its own weight from the top of the cavity, when the heat of summer or the hot rays of the sun soften the filling. An advantage of the longitudinal joint or juncture (when open) is that rain water readily runs out which is not usually the case with transverse joints or junctures. 110 115 120 125 130 135

From the foregoing, it is thought that the construction, operation and many advantages of the herein described invention will be apparent to those skilled in the art, without further description, and it will be understood that various changes in the size, shape, proportion, and minor details of this method may be resorted to without departing from the spirit or sacrificing any of the advantages of the invention.

Having thus described my invention, I claim:

1. A method of filling a cavity in a tree which consists in securely fastening to the back and sides of the cavity strips of wood arranged longitudinally of the tree and of a length equal to that of the portion of the cavity in which they are placed, filling the remainder of the cavity with like strips with their adjacent sides and ends overlapping and binding them securely in place.

2. A method of filling a cavity in a tree which consists in securely fastening to the back and sides of the cavity waterproofed or antiseptic strips of wood arranged longitudinally of the tree and of a length equal to that of the portion of the cavity in which they are placed, filling the remainder of the cavity with like strips with their adjacent sides and ends overlapping and binding them securely in place; the joints or spaces between the strips are filled with a suitable waterproof and antiseptic plastic and adhesive substance, or a mixture of such substances.

In testimony whereof, I affix my signature in the presence of two subscribing witnesses.

JAMES FRANKLIN COLLINS.
